UNITED STATES PATENT OFFICE

2,505,322

REFRIGERATOR CABINET

Earl D. Drake, Greenville, Mich., assignor to Gibson Refrigerator Company, Greenville, Mich., a corporation of Michigan

Application September 14, 1945, Serial No. 616,248

12 Claims. (Cl. 62—89)

1

This invention relates to refrigerator cabinets and more particularly to the shelves and the arrangement of the shelves within the cabinet.

Heretofore it has been common practice to provide within a refrigerator cabinet a plurality of shelves formed of metallic bars or the like to support articles within the cabinet and at the same time permit free circulation of air within the cabinet. In some instances shelves made of glass or other imperforate transparent material have been employed. Glass shelves have certain advantages over the ordinary grid type of shelf. Among the advantages are attractive appearance and ease of cleaning. Another advantage lies in the fact that imperforate glass shelves make it possible to control the temperature and humidity conditions within the cabinet to some extent.

On the other hand, glass shelves are relatively heavy, and when the entire shelf is made of glass, such shelves tend to restrict unduly the free circulation of air within the cabinet.

The present invention overcomes to a considerable extent the disadvantages of glass shelves previously used while retaining the principal advantages thereof. These desirable results are attained by providing a plurality of shelves in which a relatively large section thereof is formed of glass or similar transparent material and is removably mounted on the remainder of the shelf which is of foraminous construction to permit free circulation of air. It has been discovered that if the total area of the openings in the shelf constitute at least one-eighth of the area of the shelf the free circulation of air is not impeded to any great extent, and temperatures throughout the refrigerator cabinet are substantially uniform. The glass section improves the overall appearance of the shelf, making it very attractive to the user, but inasmuch as the glass section is of smaller overall area than the entire shelf the weight of the glass section is substantially reduced, making it more easily removed for cleaning.

One of the objects of the invention is to provide a refrigerator cabinet having a plurality of shelves therein of the type mentioned above which combine the advantages of both glass shelves and metallic grid shelves while eliminating most of the disadvantages of both types.

Another object is to provide a shelf of this character which is of especially economical construction.

These objects will more fully appear in the fol-

2

lowing specification when read in the light of the accompanying drawings, wherein:

Figure 1 is a pictorial view of a refrigerator cabinet embodying the invention with the door of the cabinet removed to show the interior thereof;

Figure 2 is a plan view of a shelf embodying the invention;

Figure 3 is a fragmentary plan view of the shelf frame;

Figure 4 is a cross-sectional view taken on substantially the line 4—4 of Figure 2;

Figure 5 is a cross-sectional view taken on substantially the line 5—5 of Figure 2;

Figure 6 is a fragmentary cross-sectional view taken on substantially the line 6—6 of Figure 2;

Figure 7 is a fragmentary cross-sectional view taken on substantially the line 7—7 of Figure 2;

Figure 8 is a pictorial view of a refrigerator cabinet embodying a modified form of the invention, the door of the cabinet being removed to show the interior thereof;

Figure 9 is a plan view of a modified form of shelf employed in the cabinet shown in Figure 8; and

Figure 10 is a cross-sectional view of the shelf taken on substantially the line 10—10 of Figure 9.

Referring now to the drawings in more detail, Figure 1 shows a refrigerator cabinet of conventional design in which a plurality of shelves embodying the invention are placed. The refrigerator cabinet is designated generally by the numeral 10. The cabinet is provided with a food storage chamber 11. In the top of the food storage chamber is a cooling evaporator 12 for refrigerating the interior of the chamber 11. At vertically spaced intervals between the evaporator 12 and the bottom of the food storage chamber 11 are a number of food supporting shelves 13, 16 and 17. Although top shelf 13 appears in Figure 1 to be different from the other shelves, all three shelves are of identical construction. The different appearance is due to the fact that the center section of the topmost shelf 13 has been

removed to accommodate tall bottles or other receptacles 14 positioned upon the intermediate shelf 16. A generally rectangular pan shaped receptacle 15 has been located upon the bottom shelf 17. Preferably the receptacle 15 has a depth substantially the same as the distance between the two shelves 16 and 17. The purpose of this arrangement will appear presently.

In general, each shelf comprises a frame 18, a pair of article supporting end sections 19 and 20 and an intermediate or center section 21. The

general arrangement of these sections is disclosed in Figure 2.

The frame 18 comprises a relatively heavy bar of metal or other suitable material bent into the shape illustrated in Figure 3. It will be seen that the frame surrounds the back and two ends and portions of the front of the shelf. The space between the ends of the bar at the front of the frame are closed by a part of the center section of the shelf, as will be more clearly described presently.

The two end sections 19 and 20 of the shelf are herein shown as perforated stampings, although it is obvious that they may be a grid of bars suitably secured together, if desired. Each end section is of generally rectangular configuration and is provided about its perimeter with downwardly and inwardly curved flanges 22, as shown in cross-section in Figures 4 and 7. The flanges 22 fit over the bar forming the frame 18 and hold the end sections in place on the frame in the position illustrated in full lines in Figure 2 and in dotted lines in Figure 3. In each end section are a plurality of elongated slots 23. The particular arrangement of the slots is unimportant, but the over all area of the slots in the two end sections should be large enough to permit circulation of air within the food storage chamber, and should not be less than one-eighth of the total shelf area.

The center section 21 is for the most part formed from a sheet of glass 24. It will be evident that instead of glass, other materials may be used, but preferably a transparent, easily cleaned material should be used. The glass sheet is imperforate. The back edge of the glass 24 is protected and supported by rear supporting member 25. This supporting member is composed of a thin strip of metal bent into the cross-sectional configuration disclosed in Figure 5. It comprises a forwardly opening channel 26 at the forward edge of the rear supporting member 25 and a downwardly opening channel 27 at the rear edge thereof. The channel 26 embraces the rear edge of the plate 24. In order to firmly hold the glass and eliminate chipping of the edge of the glass plate, a thin strip of rubber or similar cushioning material 28 is placed between the channel 26 and the glass plate.

The front edge of the glass plate 24 is ornamented and supported by a front supporting member 29. The front supporting member 29 preferably is fashioned of metal bent into channel shape, as shown in Figure 6. The channel receives the front edge of the glass plate 24. A thin strip of rubber or other cushioning material 30 is placed between the flanges of the channel and the glass 24.

The front supporting member 29 extends laterally beyond the side edges of the plate 24 a substantial distance, as seen in Figure 2. Thus, when the center section 21 is placed in its correct position relative to the rest of the shelf, the top and bottom flanges of the channel shaped supporting member 29 embrace the top and bottom surfaces of the end sections 19 and 20 of the shelf. The flanges of the supporting member 29 thus support the center section upon the rest of the shelf.

The center section 21 of the shelf is supported upon the remainder of the shelf entirely by means of the front supporting member 29 and the rear supporting member 25. The front supporting member, due to the engagement of the flanges thereof with the top and bottom surfaces of the end sections of the frame, furnish

vertical support for the front edge of the center section. The rear supporting member 25 provides both vertical support for the center section 21 and prevents horizontal movement of the shelf. The latter result is achieved because of the reception of the frame member 18 within the channel 27 in the member 25. This construction is particularly well shown in Figure 5 which shows at the left hand side thereof the engagement of the flanges of the supporting member 29 with the end sections, and at the right hand side the engagement of the frame member 25 with the frame 18.

The center section can be readily removed from the remainder of the shelf by lifting the rear edge of the shelf a sufficient distance to clear the member 25 from the member 18 and then moving the entire center section of the shelf forwardly until the flanges of the member 29 are disengaged from the end sections 19 and 20. The shelf can then be removed for cleaning or to permit the storage within the cabinet of receptacles of greater height than the distance between two shelves.

Since the center section of each shelf is imperforate and of relatively poor heat conducting material, those sections may be employed along with a suitable receptacle to provide centrally located storage zones of relatively high humidity within the food storage chamber. Thus, an ordinary pan shaped receptacle, such as receptacle 15, can be placed upon one shelf directly beneath the imperforate section of the shelf above it, and if the receptacle is of but slightly less height than the distance between the shelves, air circulation between the receptacle and the exterior thereof is substantially prevented. In other words, the center section of one shelf can be used to form a cover for a receptacle placed immediately therebelow. This is particularly advantageous in the case of the next to the topmost shelf which is relatively close to the cooling evaporator. Thus, relatively low temperatures with high humidity can be maintained within the receptacle.

Figures 8 to 10 disclose a modified form of the invention in which the topmost shelf is of somewhat different construction than the other two shelves of the cabinet. The cabinet is designated by the numeral 50 and has therein a food storage chamber 51. In the top of the food storage chamber is a cooling evaporator 52 which may be of any suitable type.

Within the food storage chamber and located at vertically spaced intervals therein are three shelves 53, 54 and 55. The two shelves 54 and 55 may be of the same construction as the shelves 13, 16 and 17 previously described, that is, formed with foraminous end sections and imperforate center sections. Shelf 53, however, is somewhat different than the other shelves, particularly in the fact that the center section is of foraminous construction and the end sections are imperforate. It will be noted that this is exactly the reverse of the shelves previously described.

The shelf comprises a frame 56, preferably of angular cross-section, bent into the shape shown in Figure 9. It will be noted that there are two end sections 57 of the frame which support removable glass plates 58. These plates are supported on the horizontal flanges of the angular frame and are easily lifted out for cleaning when desired.

The central section of the shelf comprises front

75 and rear frame members 59 and 60 respectively

which may be of the same configuration as the members 29 and 25 of the shelf shown in Figures 2 to 7. Intermediate the frame members 59 and 60 and rigidly secured thereto are a plurality of spaced apart bars 61 which run from the front to rear of the shelf. These bars constitute a grid work for supporting articles placed thereon. This central section of the shelf is applied and removed from the remainder of the shelf in exactly the same manner as the center section 21 in the shelf shown in Figures 2 to 7.

It will be evident that instead of employing a plurality of separate bars to connect the front and rear frame members 59 and 60, the central section may be formed of a perforated stamping similar to the members 19 and 20 in the previously described shelf. This particular feature of the construction is purely a matter of design.

It will be evident from an inspection of Figure 8 that the circulation of air within the cabinet is caused to follow a more or less sinuous pathway due to the fact that the cold air dropping downward from the evaporator will be diverted toward the center of the cabinet by the imperforate end sections 58. As the air continues its downward movement it then strikes the imperforate center section of the intermediate shelf by which it is diverted toward the sides of the cabinet. This arrangement has a tendency to create a very uniform temperature within the entire refrigerator cabinet.

The relative proportions of the areas of openings in the shelf and the shelf itself are not especially critical, but in order to permit enough circulation of air to maintain the desired uniform temperature conditions within the cabinet the area of the openings in the shelf must constitute at least one-eighth of the total area of the shelf.

The scope of the invention is indicated in the appended claims.

I claim:

1. A refrigerator comprising a cabinet having a food storage chamber therein, means adjacent the top of the chamber for cooling the latter, an article supporting shelf below and spaced from said cooling means, said shelf comprising an imperforate central section and a pair of foraminate end sections, and a second article supporting shelf below said cooling means and spaced therefrom and from said first named shelf, said second shelf comprising a foraminate central section and a pair of imperforate end sections.

2. A refrigerator as defined in claim 1 wherein the areas of the central and end sections in the first named shelf correspond to the areas of the end and central sections respectively in the second shelf.

3. A cabinet shelf including a unitary article supporting structure comprising a pair of laterally spaced apart foraminate article supporting end sections and a connecting member secured to said end sections for holding the same in fixed coplanar relationship relative to each other, and an imperforate article supporting central section removably attached to said structure in the space between said end sections, said central section being provided with a pair of laterally extending projections at one transverse edge thereof, said projections overlapping the corresponding transverse edges of said end sections and being movably mounted thereon.

4. A cabinet shelf including a unitary article supporting structure comprising a pair of later-

ally spaced apart foraminate article supporting end sections, one of said end sections having transverse edges substantially aligned with corresponding transverse edges of the other end section, a connecting member secured to said end sections adjacent one pair of corresponding transverse edges for holding the end sections in fixed coplanar relationship relative to each other, and an imperforate article supporting central section removably attached to said supporting structure, said central section having a portion thereof mounted upon said connecting member, said central section being provided with a pair of laterally extending projections at one transverse edge thereof overlapping the transverse edges of said end sections remote from said connecting member.

5. A cabinet shelf as defined in claim 4 wherein said projections comprise channel members having horizontal flanges, said channel members receiving the adjacent transverse edges of said end sections.

6. A refrigerator comprising a cabinet having a food storage chamber therein, means adjacent the top of the food storage chamber for cooling the latter, a plurality of vertically spaced apart article supporting shelves in said chamber below said cooling means, said shelves being substantially coextensive with the horizontal cross-sectional area of said chamber, one of said shelves comprising a pair of imperforate end sections and a foraminate central section, and another shelf having an imperforate central section and a pair of foraminate end sections, said central sections being removably connected to the respective shelves and interchangeable with each other.

7. A refrigerator as defined in claim 6 wherein said shelves are removably mounted in said cabinet.

8. A refrigerator as defined in claim 6 wherein in the horizontal area of said cooling means is substantially coextensive with the horizontal cross-sectional area of said storage chamber.

9. A refrigerator comprising a cabinet having a food storage chamber therein, means adjacent the top of the food storage chamber for cooling the latter, a plurality of vertically spaced apart article supporting shelves in said chamber below said cooling means, said shelves being substantially coextensive with the horizontal cross-sectional area of said chamber, the uppermost shelf comprising a pair of imperforate end sections and a foraminate central section, and another shelf having an imperforate central section and a pair of foraminate end sections, said central sections being removably connected to the respective shelves and interchangeable with each other.

10. A refrigerator, comprising a cabinet having a food storage chamber therein, means adjacent the top of the food storage chamber for cooling the latter, a plurality of vertically spaced article supporting shelves in said chamber below said cooling means and forming compartments in said chamber, said shelves having open portions therein adapted to receive removable shelf sections, and an imperforate and a foraminate shelf section adapted to be received and supported interchangeably in said open shelf portions to control communication between the compartments of said chamber.

11. A refrigerator, comprising a cabinet having a food storage chamber therein, means adjacent the top of the food storage chamber for cooling the latter, a plurality of vertically spaced article supporting shelves in said chamber below said cooling means, one of said shelves being sub-

stantially imperforate and comprising two separable sections, one of said sections extending substantially from front to rear of said shelf and being removable therefrom, another of said shelves comprising two separable sections, one of said sections being bodily removable from the remainder of the shelf and having substantially the same dimensions as the removable section in the said imperforate shelf whereby said removable sections can be interchanged with each other.

12. A refrigerator comprising a cabinet having a food storage chamber therein, means adjacent the top of the food storage chamber for cooling the latter, a plurality of vertically spaced article supporting shelves in said chamber below said cooling means, one of said shelves being substantially imperforate and comprising two separable sections, one of said sections extending substantially from front to rear of said shelf and being removable therefrom, said last mentioned section when removed from said imperforate shelf

being adapted to be mounted on another of said shelves.
